MINE CONDUCTOR SUPPORT

Albert H. Genter, Ross Township, Allegheny County, Pa., assignor to Duquesne Mine Supply Company, Pittsburgh, Pa., a corporation of Pennsylvania

Application September 18, 1940, Serial No. 357,287

3 Claims. (Cl. 191—40)

This invention relates generally to trolley wire supports and more particularly to hangers for supporting and carrying a trolley wire conductor and a trolley wire feeder.

This invention may be advantageously employed for use with trolley wire systems in coal mines where overhead spacing is limited.

The principal object of this invention is the provision of an improved hanger clamp for supporting a trolley wire conductor and a feeder conductor wherein the two conductors are electrically connected through the medium of the hanger clamp.

Another object is the provision of a compact hanger clamp for supporting a trolley wire conductor and a feeder conductor within the least possible head room in a mine.

Another object is the provision of a hanger clamp for supporting a plurality of conductors in subjacent relation within a mine, wherein the low ceiling limits the head room, thereby producing conditions in the ordinary overhead electrical transmission systems detrimental to safe transportation and other operations conducted in the mine.

Another object is the provision of an improved hanger clamp which is simple in construction and may be readily installed or worked.

Other objects and advantages appear in the following description and claims.

In the accompanying drawing a practical embodiment illustrating the principles of this invention is shown, wherein:

Fig. 1 is a side elevation of the hanger clamp supporting a trolley wire conductor and a feeder conductor.

Fig. 2 is a vertical section taken along the longitudinal axis of the conductors.

Fig. 3 is a vertical section taken on the line 3—3 of Fig. 1 with parts being broken away.

Fig. 4 is a vertical section taken on the line 4—4 of Fig. 1 with parts being broken away.

Referring to the drawing, 10 represents the roof or ceiling of the mine which is drilled for receiving an expansion fitting to which the upwardly extending boss 11 of the insulator 12 is secured. The circular plate 13 is an integral part of the insulator and its upper surface is arranged to fit up against the surface of the ceiling 10 forming a stop shoulder. This plate also covers the hole to protect it and prevent material from dropping out and loosening the expansion fitting. The insulating material is molded into the bell and is arranged to support the depending stud 14. When installed this in-

sulator is thus adapted to receive a hanger for carrying electrical conductors closely adjacent the ceiling of the mine. These insulators may be positioned high on the side walls or at any convenient place on the ceiling of the mine for supporting feeders or signal conductors and the like through the mine tunnels.

The structure of the hanger clamp 15 comprising this invention is arranged to support a trolley wire conductor 16 and a feeder conductor 17 in the same vertical plane. Since the hanger is constructed to carry a trolley wire the insulator 12 would be placed in the ceiling of the mine above the location of the trolley pole of a mine locomotive.

The hanger clamp 15 is made in two parts 18 and 19, each of which is provided with a central body portion 20 having oppositely extending arms 21 disposed longitudinally of the axis of the feeder conductor 17 with their outer ends 22 projecting thereabove. The ends 22 of the arms are provided with aligned holes 23 for receiving the clamping bolts 24. The holes on one clamp member are squared to prevent the bolt from turning when the nut is being tightened thereon as indicated at 25 on the drawing.

An upwardly extending boss 26 is formed integrally on the central body portion 20 of the clamp member 18. This boss is provided with a vertically threaded opening 27 for receiving the stud 14 depending from the insulator 12. Thus the hanger clamp 15 is supported from the insulators by one of the hanger clamp members.

The inner faces of the body portions 20 and the arms 21 of the clamp members 18 and 19 are provided with mating grooves 30, which are approximately semicircular, for receiving the feeder conductor 17.

The inner faces adjacent the lower edges of the body portions 20 are also provided with the small longitudinally extending grooves 31 forming opposed longitudinally extending gripping fingers 32 along the bottom edges of the body portions 20. These fingers are arranged to grip and support the trolley wire in its preformed longitudinal grooves. If the cross section of the wire is figure eight in shape the upper smaller portion will be received by the corresponding grooves 31 and the fingers 32 will grip the wire in the same manner.

The grooves 30 and 31, together with their spacing, are constructed so that one size of hanger clamp will grip a four naught, six naught, or a number nine size trolley wire in the lower grooves 31 to properly support the same under

heavy loads and still provide sufficient clamping pressure for a one million or a seven hundred and fifty thousand circular mills feeder conductor in the grooves 30. For wire sizes smaller than these a smaller size hanger clamp is required. Again shims or fillers may be supplied in the grooves 30 if the combination is such that the conductor carried by these mating grooves is relatively small in comparison with the trolley wire.

The land section 33 intermediate the parallel grooves 30 and 31 is constructed to provide sufficient clearance between the flaring flanges of a worn trolley wheel or shoe and the bolt 24 and at the same time provide ample clamping pressure on the feeder conductor 17 when the trolley wire 16 is tightly clamped by reason of the distance between the gripping fingers 32 and the fulcrum points 34 on the upper inner faces of the ends 22 of the arms 21. Thus the clamp members 18 and 19 engage one another only at the fulcrum points 34 which are located above the bolts 24.

The outer ends 22 of the arms 21 are spaced from the bell portion of the insulator 12 at approximately the same distance as the boss 26 is from the inner edge of the bell portion. This provides ample clearance to prevent an electrical discharge between these points and also provides sufficient mechanical clearance to permit tightening or loosening the bolts 24 with safety. Again it will be noted that the upper surface of the ends 22 of the arms 21 are approximately at the same elevation as the top of the boss 26. This construction thus provides a compact mechanical structure which may be readily assembled and installed.

With this construction minimum head room is utilized in suspending the trolley wire which is a vital and important factor in suspending a trolley system in a mine.

I claim:

1. In a trolley wire support arranged to carry a plurality of conductors, the combination of a hanger having a downwardly open bell member, an insulated stud depending from the bell member, a pair of complementary jaw members, at least one of said jaw members being attached intermediate of its ends to the stud, each jaw member consisting of an intermediate body portion and arms at either end of the body portion extending upwardly and outwardly to provide safety gaps between the arms and the bell mem-

ber, said jaw members provided with a plurality of grooves formed in the inner faces thereof and in subjacent relation to each other, the corresponding grooves on the jaw members registering to receive the conductors, surfaces on the arms adjacent the free extremities thereof disposed to engage and form fulcrums between the two jaw members, and means effective between each fulcrum and the grooves for causing the jaw members to converge and support the conductors in said grooves.

2. A portable trolley wire clamp arranged intermediate of its ends for insulated support from above and to carry a plurality of conductors, comprising a pair of complementary jaw members each consisting of an intermediate body portion and arms at either end of the body portion extending upwardly and outwardly to provide safety gaps between the arms and the support said jaw members provided with a plurality of grooves formed in the inner faces thereof and in subjacent relation to each other, the corresponding grooves on the jaw members registering to receive the conductors, surfaces on the arms adjacent the free extremities thereof disposed to engage and form fulcrums between the two jaw members, and means effective between each fulcrum and the grooves for causing the jaw members to converge and support the conductors in said grooves.

3. A portable trolley wire clamp arranged to carry a plurality of conductors, consisting of a pair of complementary jaw members each having an intermediate body portion, connector means formed integral with the body portion of one of said jaw members and disposed with its axis in the plane separating the jaw members for supporting the clamp, arms on either end of each jaw member extending upwardly and outwardly and spaced from said connector means, a pair of grooves formed in the inner face of each jaw member in subjacent relation to each other, the corresponding grooves on the jaw members registering to receive the conductors, surfaces on the arms adjacent the free extremities thereof disposed to engage and form fulcrums between the two jaw members, aligned transverse holes in the arms between each fulcrum and the grooves, and clamping bolts extending through said holes for causing the jaw members to converge and support the conductors in said grooves.

ALBERT H. GENTER.
